(57) **ABSTRACT**

A system for controlling rain water flow includes a container having a top end and an opposite bottom end. A drain tube having a drain port is connected to the container. A cover tube slidably receives the drain tube. A magnetic latch is disposed between the drain tube and the cover tube. The system includes a fill configuration in which the magnetic latch is magnetically engaged and the cover tube covers and seals the drain port of the drain tube. The system also includes a drain configuration in which the magnetic latch is magnetically disengaged and the drain tube slides downward to expose the drain port.

SYSTEM FOR CONTROLLING RAIN WATER FLOW

CROSS REFERENCE TO RELATED APPLICATION

None

TECHNICAL FIELD

The present invention pertains generally to controlling the flow of water, and more particularly to a system which controls the flow of rain water from a gutter.

BACKGROUND OF THE INVENTION

Rain chains are known in the art. These devices are a decorative substitute for the conventional enclosed gutter downspouts. The chains hang down from the gutter and direct rain water into a collection vessel such as an urn or simply onto the ground.

BRIEF SUMMARY OF THE INVENTION

The present invention is directed to a system for controlling rain water flow. The system hangs from the gutter of a structure. Rain water from the gutter outlet flows into a container of the system. When the weight of the collected rain water reaches a certain value, a magnetic latch is disengaged and water is discharged in a tight downward vertical stream to a collection vessel such as an urn disposed below.

When sufficient rain water has drained out of the container the container becomes light enough so that a spring can pull the container back up and again engage the magnetic latch. The container then fills again and the cycle is repeated so long as rain water is available. The system provides an interesting and aesthetically pleasing alternative to conventional downspouts or rain chains.

While the system is primarily designed for controlling rain water flow, other water flow applications are possible.

In accordance with an embodiment, a system for controlling rain water flow includes a container which has a top end and an opposite bottom end. A drain tube having a drain port is connected to the container. A cover tube slidably receives the drain tube. A magnetic latch periodically connects the drain tube and the cover tube. The system has a fill configuration in which the magnetic latch is magnetically engaged and the cover tube covers and seals the drain port of the drain tube. The system also has a drain configuration in which the magnetic latch is magnetically disengaged and the drain tube slides downward to expose the drain port.

In accordance with another embodiment, a seal is disposed at the bottom end of the container. The cover tube has a bottom end which in the fill configuration abuts the seal.

In accordance with another embodiment, the magnetic latch includes (1) the cover tube having a top end and an opposite bottom end, a magnetic adjustment screw is disposed at the top end of the cover tube, and (2) the drain tube having a top end and an opposite bottom end, the a magnet is disposed at the top end of the drain tube. In the fill configuration the adjustment screw and the magnet are magnetically engaged. In the drain configuration the adjustment screw and the magnet are magnetically disengaged.

In accordance with another embodiment, the magnetic adjustment screw is positionable toward the magnet to increase magnetic attraction and increase flow of the rain

2

water. Conversely, the magnetic adjustment screw is positionable away from the magnet to decrease magnetic attraction and decrease flow of the rain water.

In accordance with another embodiment, the cover tube has a top end. A spring is connected between the top end of the cover tube and the bottom of the container. The spring biases the container in an upward direction.

In accordance with another embodiment, the cover tube has a top end. A distance limiter is connected between the top end of the cover tube and the bottom end of the container. The distance limiter limits a downward distance travelled by the drain tube.

In accordance with another embodiment, the system continuously cycles between the fill configuration and the drain configuration.

In accordance with another embodiment, a container is vertically positionable to an up position and to a down position. A drain port is connected to the container, the drain port being covered when the container is in the up position, and the drain port being exposed when the container is in the down position; A magnetic latch magnetically holds the container in the up position. In a fill configuration in the magnetic latch is magnetically engaged and the container can fill with the rain water. In a drain configuration the magnetic latch is magnetically disengaged and the rain water can drain from the container.

In accordance with another embodiment, a container is vertically positionable to an up position and to a down position. A drain port is connected to the container, the drain port being covered when the container is in the up position, and the drain port being exposed when the container is in the down position; A magnetic latch is positionable to a mechanically engaged position wherein the container is disposed in the up position and the container can fill with rain water. The magnetic latch is positionable to a magnetically disengaged position wherein the container is disposed in the down position and rain water can drain from the container.

Other embodiments, in addition to the embodiments enumerated above, will become apparent from the following detailed description, taken in conjunction with the accompanying drawings, which illustrate, by way of example, the principles of the system for controlling rain water flow.

BRIEF DESCRIPTION OF THE DRAWINGS

FIG. 1 is a top plan view of a system for controlling the flow of rain water;

FIG. 1 is a perspective view of the system;

FIG. 3 is a reduced exploded view of the system;

FIG. 4 is a cross sectional view along the line 4-4 of FIG. 1 showing the system in a fill configuration;

FIG. 5 is a cross sectional view as in FIG. 4 showing the system in a drain configuration;

FIG. 6 is an elevation cutaway view of the system in the fill configuration;

FIG. 7 is an elevation cutaway view of the system in the drain configuration;

FIG. 8 is an elevation cutaway view of the system rotated 90 degrees from FIG. 7;

FIG. 9 is a reduced perspective view of the system installed on a gutter; and,

FIG. 10 is a reduced perspective of the system with a decorative cover.

DETAILED DESCRIPTION OF THE INVENTION

Referring initially to FIGS. 1-8 there are shown several views of a system for controlling rain water flow, the

system generally designated as **20**. System **20** includes a container **22** (such as a bucket) for collecting the rain water **500**. Container **22** has a top end **24** (a mouth for receiving rain water **500**) and an opposite bottom end **26** (a base and components attached closely thereto). A drain tube **28** having a drain port **30** is connected to the bottom end **26** of container **22** and upwardly projects therefrom. Drain port **30** is an opening in drain tube **28** which allows water to drain from system **20**. In the shown embodiment there are four drain ports **30** separated by thin sections of drain tube **28** (refer to FIG. 3). In an embodiment container **22** is 6.5 inches deep and has a 6 inch diameter mouth.

A cover tube **32** slidably receives drain tube **28**, wherein drain tube **28** slides up and down with respect to cover tube **32** which is stationary when system **20** is in use. To that end, a hanger **34** (such as the shown loop) is connected to cover tube **32**, and hanger **34** is connected to the gutter **600** (refer to FIGS. 9 and 10).

System **20** further includes a magnetic latch which periodically connects drain tube **28** and cover tube **32**. In the shown embodiment, the magnetic latch includes (1) cover tube **32** having a top end and an opposite bottom end, a magnetic adjustment screw **36** (made of a magnetic material such as steel) is disposed at the top end of cover tube **32**, and (2) drain tube **28** having a top end and an opposite bottom end, a magnet **38** is disposed at the top end of drain tube **28**. In an embodiment magnet **38** is a neodymium magnet N42SH, $1/4$ " thick $\times 3/4$ " dia. Pull force 12.8 lbs.

Referring to FIGS. 4 and 6, system **20** includes a fill configuration in which the magnetic latch is magnetically engaged and cover tube **32** covers and seals drain port **30** of drain tube **28** (refer to FIGS. 4 and 6). That is, magnetic adjustment screw **36** and magnet **38** are magnetically engaged (magnetically pulled together) wherein the magnetic attraction of magnet **38** and magnetic adjustment screw **36** cause fill tube **28** (and container **22**) to be pulled and remain up. System **20** further includes a downspout **37** which directs the rain water **500** in a downward stream. When in the fill configuration rain water **500** fills container **22**.

Referring to FIGS. 5, 7, and 8 system **20** also includes a drain configuration in which the magnetic latch is magnetically disengaged and drain tube **28** slides down to expose drain port **30** (refer to FIGS. 5 and 7). That is, magnetic adjustment screw **36** and magnet **38** are disengaged so drain tube **28** can slide down with respect to cover tube **32** to expose drain port **30** and allow water to drain from container **22**. After a sufficient amount of rain water **500** drains from container **22** and the weight of the container is less, a spring (see discussion below) urges container **22** with drain tube **28** up until magnetic latch **32** again engages. The fill/drain cycle is then repeated. That is, system **20** continuously cycling between the fill configuration and the drain configuration. When in the drain configuration rain water **500** drains out of container **22** and through downspout **37** as is shown by the arrows. In an embodiment it takes about 16 ounces of rain water **500** to disengage the magnetic latch and trigger the drain configuration.

Magnetic adjustment screw **36** creates the ability to increase or decrease the magnetic bond with magnet **38**. This in turn increases or decreases the amount of water **600** needed to transition from the fill configuration to the drain configuration. For example referring to FIG. 4, if magnetic adjustment screw **36** is screwed downward with respect to cover tube **32** and magnet **38**, the magnetic attraction with magnet **38** will increase and it will take more rain water **500**

to initiate the drain cycle. This will cause system **20** to cycle less frequently, and to release a larger flow of rain water **500** upon discharge.

Conversely, if magnetic adjustment screw **36** is screwed upward with respect to cover tube **32** and magnet **38**, the magnetic attraction with magnet **38** will decrease and it will take less rain water **500** to initiate the drain cycle. This will cause system **20** to cycle more frequently, and to release a smaller flow of rain water **500** upon discharge.

To effect the sealing of drain port **30** of drain tube **28** in the fill configuration, a seal **40** is disposed at bottom end **26** of container **22**. Cover tube **32** has a bottom end which abuts seal **40** in the fill configuration. In the shown embodiment a flange is disposed at the bottom end of cover tube **32**, the flange abuts seal **40** (refer to (FIGS. 4 and 6).

1. A spring **42** is connected between top end of cover tube **32** and the bottom end **26** of container **22**. In the shown embodiment two springs **42** are utilized. Spring **42** biases container **22** in an upward direction. Spring **42** pulls container **22** up when the weight of the rain water **500** is reduced through draining, so that magnetic latch **36** can engage to start the next fill cycle (refer to FIGS. 4 and 6). It is noted that in FIGS. 4 and 6 springs **42** are not shown in cross section for clarity. In an embodiment spring **42** is an extension spring $0.25" \times 3.25" \times 0.025"$.

Referring to FIGS. 5, 7, and 8 system **20** further includes a distance limiter **44** (such as a chain) connected between the top end of cover tube **32** and the bottom end **26** of container **22** (two distance limiters in the shown embodiment). Distance limiter **44** limits the downward distance travelled by container **22** and drain tube **30** in the drain configuration.

Referring now to FIGS. 9 and 10, there are illustrated reduced perspective views of system **20** installed on a gutter **600**, and the system with a decorative cover. A structure has a rain gutter **600**. System **20** is connected to rain gutter **600** so that the rain water **500** flows into container **22**. As discussed above the connection is made using a hanger **34** connected to cover tube **32**. Rain water **500** flows out of a downspout **37** connected to the bottom of container **22**, and in the shown embodiment into an urn is disposed beneath system **20**. In FIG. 10 a decorative cover **46** surrounds system **20**. In an embodiment the cover **46** is illuminated such as by solar lights.

45 The embodiments of the system for controlling rain water flow described herein are exemplary and numerous modifications, combinations, variations, and rearrangements can be readily envisioned to achieve an equivalent result, all of which are intended to be embraced within the scope of the appended claims. For example, container size, magnets, and springs can be selected to achieve any desired operational result. Further, nothing in the above-provided discussions of the system should be construed as limiting the invention to a particular embodiment or combination of embodiments. The scope of the invention is defined by the appended claims.

I claim:

1. A system for controlling rain water flow comprising: a container having a top end and an opposite bottom end; a drain tube connected to said container, said drain tube having a drain port; a cover tube which slidably receives said drain tube; a magnetic latch which periodically connects said drain tube and said cover tube; a fill configuration in which said magnetic latch is magnetically engaged and said cover tube covers and seals said drain port of said drain tube; and,

5

- a drain configuration in which said magnetic latch is magnetically disengaged and said drain tube slides downward to expose said drain port.
2. The system according to claim 1 further including: a seal disposed at said bottom end of said container; and, said cover tube having a bottom end which in said fill configuration abuts said seal. 5
3. The system according to claim 1 further including: said magnetic latch including (1) said cover tube having a top end and an opposite bottom end, a magnetic adjustment screw disposed at said top end of said cover tube, and (2) said drain tube having a top end and an opposite bottom end, a magnet disposed at said top end of said drain tube; 10 in said fill configuration said adjustment screw and said magnet being magnetically engaged; and, in said drain configuration said adjustment screw and said magnet being magnetically disengaged.
4. The system according to claim 3 further including: said magnetic adjustment screw positionable toward said magnet to increase magnetic attraction; and, said magnetic adjustment screw positionable away from said magnet to decrease magnetic attraction. 15
5. The system according to claim 1 further including: said cover tube having a top end; a spring connected between said top end of said cover tube and said bottom end of said container; and, said spring biasing said container in an upward direction. 20
6. The system according to claim 1 further including: said cover tube having a top end; a distance limiter connected between said top end of said cover tube and said bottom end of said container; and, said distance limiter limiting a downward distance travelled by said drain tube. 25
7. The system according to claim 1 further including: said system continuously cycling between said fill configuration and said drain configuration. 30
8. The system according to claim 1, the system cooperating with a rain gutter, the system further including: a hanger connected to said cover tube; and, said hanger connected to the rain gutter. 35
9. The system according to claim 1 further including: an ornamental cover which surrounds said system.
10. The system according to claim 1 further including: a seal disposed at said bottom end of said container; said cover tube having a bottom end which in said fill configuration abuts said seal; 40 said magnetic latch including (1) said cover tube having a top end and an opposite bottom end, a magnetic adjustment screw disposed at said top end of said cover tube, and (2) said drain tube having a top end and an opposite bottom end, a magnet disposed at said top end of said drain tube; 45 50

6

- in said fill configuration said adjustment screw and said magnet being magnetically engaged; in said drain configuration said adjustment screw and said magnet being magnetically disengaged; said magnetic adjustment screw positionable toward said magnet to increase magnetic attraction; said magnetic adjustment screw positionable away from said magnet to decrease magnetic attraction; a spring connected between said top end of said cover tube and said bottom end of said container; said spring biasing said container in an upward direction; a distance limiter connected between said top end of said cover tube and said bottom end of said container; said distance limiter limiting a downward distance travelled by said drain tube; and, said system continuously cycling between said fill configuration and said drain configuration.
11. A system for controlling rain water flow comprising a container which is vertically positionable to an up position and to a down position; a drain port connected to said container, said drain port being covered when said container is in said up position, and said drain port being exposed when said container is in said down position; a magnetic latch which magnetically holds said container in said up position; a fill configuration in which said magnetic latch is magnetically engaged and said container can fill with the rain water; and, a drain configuration in which said magnetic latch is magnetically disengaged and the rain water can drain from said container.
12. The system according to claim 11 further including: a spring connected to said container, said spring urging said container to said up position.
13. A system for controlling rain water flow comprising a container which is vertically positionable to an up position and to a down position; a drain port connected to said container, said drain port being covered when said container is in said up position, and said drain port being exposed when said container is in said down position; a magnetic latch positionable to a mechanically engaged position wherein said container is disposed in said up position and said container can fill with rain water; and, said magnetic latch positionable to a magnetically disengaged position wherein said container is disposed in said down position and rain water can drain from said container.
